(57) **CLAIM**

The ornamental design for a double-sided kiosk system, as shown and described.

DESCRIPTION

FIG. 1 is a front perspective view of the double-sided kiosk system showing the new design with a single center modular component;

FIG. 2 is a rear perspective view thereof;

FIG. 3 is a right-side view thereof;

FIG. 4 is a left-side view thereof;

FIG. 5 is a front view thereof;

FIG. 6 is a rear view thereof;

FIG. 7 is a top view thereof; and,

FIG. 8 is a bottom view thereof.

The broken lines in the drawings depict portions of the double-sided kiosk system that form no part of the claimed design.
